(57) **CLAIM**

The ornamental design for a cooking appliance with a burner grate, as shown and described.

DESCRIPTION

FIG. 1 is a front perspective view of the cooking appliance with a burner grate according to the design;

FIG. 2 is a front perspective view of the cooking appliance with a burner grate shown in FIG. 1 with unclaimed portions of the cooking appliance and additional burner grates that are unclaimed in FIG. 1 being removed;

FIG. 3 is a top plan view of the cooking appliance with a burner grate of FIG. 2;

FIG. 4 is a bottom plan view thereof;

FIG. 5 is a front elevation view thereof;

FIG. 6 is a back elevation view thereof;

FIG. 7 is a right side elevation view thereof; and,

FIG. 8 is a left side elevation view thereof.

The broken line showing of various features is for the purpose of illustrating unclaimed portions of the cooking appliance with a burner grate and forms no part of the claimed design.
